Patented Nov. 13, 1923.

1,473,685

UNITED STATES PATENT OFFICE.

WILLIAM B. STURGIS, OF CHICAGO, ILLINOIS, ASSIGNOR TO GENERAL EXPLOSIVES COMPANY, OF CHICAGO, ILLINOIS, A CORPORATION OF DELAWARE.

METHOD FOR PRODUCING EXPLOSIVES.

No Drawing. Original application filed July 23, 1919, Serial No. 312,671. Divided and this application filed December 31, 1921. Serial No. 526,252.

To all whom it may concern:

Be it known that I, WILLIAM B. STURGIS, a citizen of the United States, residing at Chicago, in the county of Cook and State 5 of Illinois, have invented certain new and useful Improvements in Methods for Producing Explosives, of which the following is a specification.

The object of my present invention is the 10 provision of an improved method for producing a powerful explosive which shall have a low freezing point and shall be inexpensive to manufacture.

It is known that dinitrochlorhydrin, produced by the nitration of monochlorhydrin, is an explosive having certain desirable properties, including a low freezing point, but because of the expense of producing this explosive as compared with nitroglycerin, 20 for example, its commercial manufacture has been found impracticable.

I have discovered, however, that monochlorhydrin is an extremely efficient solvent for certain inexpensive carbohydrates, such 25 as sugars, and that the nitration of a solution of monochlorhydrin and one or more carbohydrates, such as sugars, produces a very desirable explosive. Its freezing point is exceedingly low, it is easily purified and 30 stabilized, its explosive strength is substantially equal to that of nitroglycerin, and the cost of manufacture is low. This explosive contains dinitrochlorhydrin, and one or more nitrated carbohydrates.

35 It may be found desirable in some instances to include in the explosive other nitrated components, such, for example, as nitroglycerin. Such an explosive may be produced by nitrating a solution of monochlorhydrin, one or more carbohydrates, and glycerin. The final product obtained from the nitration of this last named solution and subsequent purification, contains nitroglycerin, dinitrochlorhydrin and one or 40 more nitrated carbohydrates. A solution of monochlorhydrin, carbohydrates, and glycerin may be obtained by adding the desired carbohydrates to the solution resulting from the reaction occurring between glycerin and 45 hydrochloric acid when subjected to certain conditions of temperature and pressure. Under ordinary conditions, and especially if the chlorinating process is conducted at atmospheric pressure or too high tempera-

ture, some diglycerin is usually formed. In 55 case the monochlorhydrin-carbohydrate-glycerin solution so obtained is nitrated, the resultant product will usually contain some tetranitrodiglycerin, and nitrated hydrochloric acid esters of diglycerin in addition 60 to the nitrated components above mentioned.

I have already called attention in the preceding paragraph to the fact that, in the preparation of monochlorhydrin, unless special precautions are observed, there is likely 65 to be formed an appreciable quantity of diglycerin. When this occurs and a mixture of monochlorhydrin, glycerin and diglycerin is nitrated and subsequently purified, an emulsion is very apt to form from which it 70 is more difficult to separate the wash waters. This also occurs to some extent in the purification of a nitrated solution of sugar in glycerin.

Should, however, the two solutions just 75 described be mixed together and the resultant solution nitrated and purified, a very much worse emulsion occurs, and this not only seriously interferes with the proper purification of the product but also causes 80 an increased loss in yield. For this reason it is sometimes preferable to nitrate and purify the solutions separately and then combine them in the desired proportions.

For the reasons explained above, wherever in the following claims the word "monochlorhydrin" or the expression "a solution containing monochlorhydrin" occurs, it is to be understood that this refers to the product produced by treating glycerin on a 85 commercial scale for use in the manufacture of explosives, and that said product frequently contains appreciable amounts of diglycerin, and unconverted glycerin.

In the preparation, therefore, of any of 90 the above explosives, instead of nitrating a solution containing all of the desired components, the various components may be nitrated separately or in various combinations, and the resulting nitrated products may 100 then be combined. It is to this last mentioned method of effecting the nitration that the claims of the present application, are directed, this application being a division of my co-pending application Serial No. 312,671, filed July 23, 1919, Patent No. 1,463,980 Aug. 7, 1923.

To the explosives described herein, there

may be added other ingredients which may prove desirable in the manufacture of smokeless powders and commercial explosives, such, for example, as nitrocellulose, 5 nitro-compounds, organic and inorganic nitrates (such as nitrated vegetable ivory and sodium nitrates, perchlorate), chlorates and absorbents (such as wood flour, saw-dust, etc.).

10 This invention is not limited to the particular materials, components, products, processes or methods described above, since obviously many changes may be made therein without departing from the spirit or 15 scope of my invention as set forth in the appended claims.

I claim:

1. A method of producing explosives which consists in taking two separate quantities of glycerin and monochlorhydrin in one of which is included a carbohydrate which is soluble therein, nitrating separately the two quantities, and mixing the two nitrated products together.
2. A method of producing explosives which consists in taking a quantity of glycerin and a quantity of monochlorhydrin, adding to one of said quantities a carbohydrate which is soluble therein, nitrating separately the quantity containing the carbohydrate and the other quantity, and mixing the two nitrated products together.
3. A method of producing explosives which consists in taking a quantity of glycerin and a quantity of monochlorhydrin, adding to one of these quantities more than one carbohydrate which is soluble therein, nitrating separately the quantity containing the carbohydrates and the other quantity, and mixing the two nitrated products together.
4. A method of producing explosives which consists in taking a quantity of glycerin and a quantity of monochlorhydrin, adding to one of said quantities a sugar, nitrating separately the quantity containing the sugar and the other quantity, and mixing the two nitrated products together.
5. A method of producing explosives which consists in taking a quantity of glycerin and a quantity of monochlorhydrin, adding to one of said quantities more

than one variety of sugars, nitrating separately the quantity containing the sugars and the other quantity, and mixing the two nitrated products together.

6. A method of producing explosives which consists in nitrating a solution containing glycerin and a carbohydrate which is soluble in glycerine, and mixing this nitrated solution with dinitrochlorhydrin.

7. A method of producing explosives which consists in nitrating a solution containing glycerin and more than one carbohydrate, which is soluble in glycerine, and mixing this nitrated solution with dinitrochlorhydrin.

8. A method of producing explosives which consists in nitrating a solution containing glycerin and a carbohydrate which is soluble in glycerine, and mixing this nitrated solution with any mixture containing dinitrochlorhydrin.

9. A method of producing explosives which consists in nitrating a solution containing a glycerin and more than one carbohydrate which is soluble in glycerine, and mixing this nitrated solution with any mixture containing dinitrochlorhydrin.

10. The method of producing explosives which consists in nitrating a solution containing glycerin and a sugar, and mixing this nitrated solution with dinitrochlorhydrin.

11. The method of producing explosives which consists in nitrating a solution containing glycerin and more than one variety of sugar, and mixing this nitrated solution with dinitrochlorhydrin.

12. The method of producing explosives which consists in nitrating a solution containing glycerin and a sugar, and mixing this nitrated solution with a mixture containing dinitrochlorhydrin.

13. The method of producing explosives which consists in nitrating a solution containing glycerin and more than one variety of sugar, and mixing this nitrated solution with a mixture containing dinitrochlorhydrin.

In testimony whereof I have hereunto subscribed my name.

WILLIAM B. STURGIS.
